K. MAYBACH

CARBURETOR

Filed May 20, 1921

INVENTOR

Karl Maybach

UNITED STATES PATENT OFFICE.

KARL MAYBACH, OF FRIEDRICHSHAFEN, GERMANY, ASSIGNOR TO THE FIRM MAYBACH-MOTORENBAU GESELLSCHAFT MIT BESCHRANKTER HAFTUNG, OF FRIEDRICHSHAFEN-ON-THE-BODENSEE, GERMANY.

CARBURETOR.

Application filed May 20, 1921, Serial No. 471,268, and in Germany May 15, 1920.

(GRANTED UNDER THE PROVISIONS OF THE ACT OF MARCH 3, 1921, 41 STAT. L., 1313.)

My invention relates to carburetors for internal combustion engines and its particular object is to render the operation of such devices safer and more effective. In order to maintain the level of the fuel in carburetors as constant as possible, a float controlled valve is provided in the fuel supply pipe. Now it may occur, that when the float valve does not operate as occurs at times when dirt causes the valve to stick, the fuel rises and finally floods the nozzle. This does not only mean a waste of fuel, but there is also the danger of the carburetor catching fire.

The present invention provides a device associated with the nozzle for taking care of any fuel overflowing therefrom in the event of the float valve failing to act and carrying such fuel to a receptacle provided for the purpose, so as to prevent escape of overflowed fuel at the engine and consequent danger of fire.

In the drawings appended to this specification and forming part thereof a device embodying my invention is illustrated in section by way of example.

From the fuel tank, not shown, a supply pipe 1 extends to the float chamber 2 and communicates therewith, the supply being controlled by a needle valve 5 which is actuated by a float 4. The float chamber is connected with a vertically arranged pipe 7 by means of a horizontal pipe 3 provided with a disk 6 having a calibrated orifice therein to restrict the flow of fuel from the float chamber, the disk being calibrated in accordance with the demand of the particular engine with which the device is to be associated.

The pipe 7 extends somewhat beyond the level maintained by the float 4 in chamber 2 so that fuel will flow over from the pipe 7 only when the float fails to operate.

Into the pipe or jacket 7 there extends a nozzle 8 having an outlet 9. Both the pipe 7 and the nozzle 8 are surrounded by a pipe 10 which connects with a suitable receptacle 11 serving to receive the fuel overflowed into the pipe 10.

In order to prevent an escape of fuel when the car is moving through a curve or uphill,

the top edge of the pipe 7 is bent inwards thereby preventing the fuel from spouting out.

A regulating device which is particularly suited for use with a carburetor according to the present invention, consists in a plurality of holes 12 in pipe 8 below the level of the fuel in float chamber 2. Such holes are preferably provided at various levels, and their numbers and diameters may differ according to their level.

A device comprising a pipe of reduced cross-sectional area and a number of holes 12 in the suction tube will operate as follows:

When the engine is running slowly or at no load, and the consumption of fuel is small, the fuel level in pipe 7 is not much below that in chamber 2. When the engine is accelerated and consumes more fuel, the level in pipe 7 begins to sink. The further it sinks, the more holes 12 are uncovered and admit an increasing quantity of air from pipe 10, so that the fuel supply is effectively reduced. The holes are so arranged and of such diameters that the desired uniformity of mixture is attained with all speeds.

I wish it to be understood that I do not desire to be limited to the exact details of construction shown and described, for obvious modifications will occur to a person skilled in the art.

I claim:—

1. Carburetor comprising in combination, a fuel chamber, means for constantly supplying fuel to said chamber, a float valve in said chamber for controlling the supply of fuel thereto, a fuel nozzle having its upper end located above the upper fuel level in said chamber, a tube surrounding said nozzle with the exception of the upper end thereof, a pipe connecting the lower part of said chamber with the lower end of said tube, and an overflow tube surrounding said tube with a clearance.

2. Carburetor comprising in combination, a fuel chamber, means for constantly supplying fuel to said chamber, a float valve in said chamber for controlling the supply of fuel thereto, a fuel nozzle extending sub-

stantially vertically alongside of said chamber with its upper end above the upper fuel level in said chamber, the wall of said nozzle having openings therein at different levels, a tube surrounding said nozzle with the exception of the upper end thereof, a pipe connecting the lower part of said chamber

with the lower end of said tube, an overflow tube surrounding said tube with a clearance and a receptacle underneath said overflow tube.

In testimony whereof I affix my signature.

KARL MAYBACH.
